HEEL FOR FOOTWEAR

George R. Rule and Alice N. Rule, Los Angeles,
Calif.

Application October 28, 1940, Serial No. 363,092

6 Claims. (Cl. 36—34)

This invention relates to heels of footwear such as shoes, pumps or the like, and the invention is particularly applicable to the heels of ladies' shoes or pumps. It is the present practice to provide a covering of thin leather or similar material for heels, and this material must be molded or stretched to the curves and contour of the heel. This material is necessarily thin and is somewhat delicate and very readily becomes scuffed; that is to say, its surface will become marred or broken so as to render the heel unsightly and unsatisfactory for further wear. In covering such a heel in that way, the covering usually includes a body portion which is molded onto the heel from the rear, with the forward edges folded over on the breast of the heel. These folded over edges are then concealed by breasting that extends down from the under side of the sole at the shank, to the bottom lift of the heel.

One of the objects of the present invention is to provide a heel with a covering which can be readily applied, and which will be highly resistant to scuffing or injury when the wearer walks over gravel, or along a pathway which might tend to injure the covering for the surface of the heel.

More specifically stated, the invention involves the use of a covering material in cord form, that is wrapped around the body of the heel so as to form a covering for it. This cord material is of course applied to the body of the heel before the heel is secured to the shoe or pump. My improvement may be applied to various styles of heels. Some heels have a forwardly projecting lip or shank tongue which substantially aligns with the out sole, for connection to the same.

One of the objects of the present invention is to provide a disposition for the coils of the cord, which will enable the same to substantially cover a forwardly projecting tongue on the heel; also to provide a disposition of the upper coils at the rear and upper end of the heel, which will enable the coils at this point to maintain substantial parallelism with the lower coils.

A further object of the invention is to provide a heel having a covering which readily lends itself to the presentation of any desired color scheme in the heel, and not necessarily including a uniform color for the entire heel.

Further objects of the invention will appear hereinafter.

The invention consists in the novel parts and combination of parts to be described hereinafter,

all of which contribute to produce an efficient heel for footwear.

A preferred embodiment of the invention is described in the following specification, while the broad scope of the invention is pointed out in the appended claims.

In the drawing:

Fig. 1 is a side elevation of a lady's pump having a high heel embodying our invention.

Fig. 2 is a side elevation showing the upper portion of a heel embodying our invention, and representing the same unattached to the body of the pump.

Fig. 3 is a plan of the heel illustrated in Fig. 2, but upon a somewhat larger scale.

Fig. 4 is a horizontal section taken about on the line 4—4 of Fig. 2, and looking upwardly.

Fig. 5 is a view similar to Fig. 2, but illustrating another type of heel to which our invention may be applied.

Referring more particularly to the parts, 1 indicates the body of a shoe or pump having a heel 2 covered in accordance with our invention. The body 3 of this heel is preferably constructed of wood or similar material, which will adhere readily to glue.

In practicing the invention, we wrap the heel body with a cord material 4 that is preferably disposed on the heel in substantially horizontal coils 5. In this way a covering composed of a wrapping of cord, is applied to the heel. The wrapping process is preferably commenced at the bottom of the heel and just above the bottom lift 6. The wrapping proceeds thence in an upward direction, disposing the coils one above the other and touching or in close proximity to each other.

Any suitable material may be used for this cord wrapping; for example, twine, wool, yarn, silk or twisted fabric. We prefer, however, to use twisted tissue paper, as glue will adhere quite readily to this material, and will be absorbed by it. In applying the cord to the body of the heel, when it becomes necessary to lay on another cord at the point of contact between the ends of the two adjoining cords, we form a scarf joint or a scarf connection 7, as indicated in Fig. 2.

Under the coils of the cord as they are applied to the surface of the heel, a layer of moist glue is placed, and the coils are applied under slight tension so that they cling closely to the surface of the heel. No substantial difficulty is experienced in applying the cord to the lower portion of the heel, but at the upper portion of the heel the application of the cord must be adapted to

the shape of the heel so as to substantially cover the forwardly projecting lip or shank tongue 8 of the heel (see Fig. 2). In order to cover this lip the upper coils that are located at about the level of the under side of the lip, are glued on to the concave face at 9, that merges the under face of the lip into the forward face or breast 10 of the heel. At this point these coils are applied with transverse extensions 11 which are glued to the under face of the heel, and which extend parallel with each other and lie against each other across the under side of the heel, as indicated in Fig. 4. When a point is reached for these coils, that will leave a sufficient amount of the lip projecting to secure the same in the shoe, we then commence to dispose the upper coils 12 in a somewhat different manner. In the heel of the type illustrated in Fig. 2, these uppermost coils 12 are laid on preferably as separate pieces, with extensions 13 lying on the upper face or heel seat 14 of the heel, and glued to the same. This is illustrated in Fig. 3. This procedure of making these coils discontinuous, is practically necessary, because the heel seat on the upper face of a heel is slightly concave, or dished. In Fig. 5 we illustrate another type of heel in which there is no concave face merging the under side of the lip into the breast of the heel. In this case the lip 8a has a substantially flat under face 15 projecting out at approximately 90° from the substantially vertical breast 16 of the heel 17. In laying on the upper coils 18 in this case, that is to say, the coils that occur above the level of the under face 15 of the lip, these coils are turned downwardly in curves 19 at their forward ends and adjacent the transverse extensions 20 that pass across the heel, and which are glued to the under face 15 of the lip. In this way, the side edges of the lip 8a can be substantially covered; and after this is accomplished the remainder of the upper coils 21 are discontinuous and have their forward ends simply laid upon the dished heel seat 22, and glued to the same in the manner indicated in Fig. 3.

After the cord has been applied so as to completely cover the outer surface of the heel, excepting for the tip of the lip which must be left uncovered, we then apply three coats of glue to the outer face of the cord covering, allowing each coat to dry before the application of the next coat. After this, we apply two coats of shellac and two coats of varnish, permitting each coat, of course, to dry before the application of the next coat. This glue applied in this way, permeates the paper cord so that the finished cord is quite hard and durable. The shellac and varnish render the cord covering substantially waterproof.

In practice, if variegated color effects are desired, this can be attained by using cords of different color, for example, several coils of one color can be followed by several coils of a contrasting color. In this way incidental attractive color schemes can be produced in the heels.

It will be evident that the practice of this invention eliminates the necessity for the use of full breasting on a heel.

What we claim is:

- 5 1. A heel for a shoe or pump having a covering consisting of a plurality of coils of a cord extending in a general horizontal direction, adhering to the surface of the heel.
- 10 2. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip.
- 15 3. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having extensions lying on the upper face of the heel and secured thereto.
- 20 4. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having their ends lying on the heel seat and secured thereto by adhesive.
- 25 5. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having their ends lying on the heel seat and secured thereto by adhesive.
- 30 6. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having their ends lying on the heel seat and secured thereto by adhesive.
- 35 7. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having their ends lying on the heel seat and secured thereto by adhesive.
- 40 8. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having their ends lying on the heel seat and secured thereto by adhesive.
- 45 9. A heel for a shoe or pump with a forwardly extending lip, said heel having a covering consisting of a plurality of coils of a cord extending in a general horizontal direction adhering to the surface of the heel, said coils in the vicinity of said lip including a set of coils encircling the heel at the rear and sides, and extending transversely on the under side of the lip; and including other coils above the said set of coils encircling the heel at its rear and sides, and having their ends lying on the heel seat and secured thereto by adhesive.
- 50 10. A heel for a shoe or pump having a covering consisting of a plurality of coils of a cord extending in a general horizontal direction, with glue securing the same to the surface of the heel, having a coating of glue applied to the coils after the same have been secured to the heel, and having a coating of shellac and a coating of varnish applied on the outer side of the shellac coating.
- 55 11. A heel for a shoe or pump having a covering consisting of a plurality of coils of a cord extending in a general horizontal direction, with glue securing the same to the surface of the heel, having a coating of shellac and a coating of varnish applied on the outer side of the shellac coating.
- 60 12. A heel for a shoe or pump having a covering consisting of a plurality of coils of a cord extending in a general horizontal direction, with glue securing the same to the surface of the heel, having a coating of shellac and a coating of varnish applied on the outer side of the shellac coating.
